B. J. Craig

ATTORNEY.

UNITED STATES PATENT OFFICE

ARTHUR E. SMITH, OF LOS ANGELES, CALIFORNIA

RECEPTACLE CLOSURE

Application filed November 15, 1926. Serial No. 148,351.

This invention relates to closures for collapsible tubes.

The general object of the invention is to provide an improved closure for collapsible tubes wherein the closure includes an automatic valve.

Another object of the invention is to provide a novel means for securing a closure upon a collapsible tube.

10 A further object of the invention is to provide an automatic valve closure which is retained in place by flanges integral with the neck of the tube.

Still another object of the invention is to 15 provide a tube having a closure thereon wherein means is provided to prevent the closure from being forced out of its proper position on the collapsible tube.

Other objects of the invention will be apparent from the following description taken 20 in connection with the accompanying drawings wherein:

Fig. 1 is a central sectional view partly in elevation showing my invention.

25 Fig. 2 is a section taken on line 2—2 of Fig. 1.

Fig. 3 is a view similar to Fig. 2 showing the closure after the valve slit has been exposed.

30 Fig. 4 is a top plan view of the device shown in Fig. 1;

Fig. 5 is a top plan view of the device shown in Fig. 3;

Fig. 6 is a top plan view of the closure 35 showing the elliptical form of the valve closure before it is inserted in the tube.

Fig. 7 is a view similar to Fig. 3 showing the valve opened by pressure of the tube contents;

40 Fig. 8 is a central sectional view partly in elevation showing another form of closure and means for sealing the valve slit.

Fig. 9 is a top plan view of the device shown in Fig. 8;

45 Fig. 10 is a central sectional view partially in elevation of a modified form of tube closure.

Fig. 11 is a view similar to Fig. 10 showing the method of making the valve opening in the closure;

Fig. 12 is a top plan view of the device shown in Fig. 11, showing the closure after the valve opening has been formed therein;

Fig. 13 is a central sectional view partly in elevation and showing another modification 55 of tube closure;

Fig. 14 is a top plan view of the device shown in Fig. 13;

Fig. 15 is a central sectional view partly in elevation of a tube closure similar to the one 60 shown in Fig. 1 but showing another means of securing the closure upon the tube;

Fig. 16 is a view similar to Fig. 15 showing the closure after the valve slit has been exposed;

Fig. 17 is a top plan view of the device 65 shown in Fig. 15, and

Fig. 18 is a view similar to Fig. 15 showing a modified form of valve closure.

Referring to the drawings by reference 70 characters I have shown my invention in connection with a collapsible tube shown at 10. In the following description I will describe my invention as used in connection with collapsible tubes and particularly for the purpose of dispensing material such as dental preparations, although it will be understood that the device is not limited to this particular use, but may be used in dispensing other plastic substances which flow more or less 75 freely.

Referring again to the drawings, the collapsible tube 10 as shown is provided with a conical end portion 11 having a cylindrical neck 12 integral therewith. The neck 12 has 80 upon its inner surface an integral flange 13 having a collar 14 thereon.

A closure which I prefer to use with this form of neck is indicated generally at 15. It comprises a body having an annular basal portion 16 and an end portion 17. The end portion consists of a transversely extending boss 18 arranged to provide a transverse cavity 19 adjacent the inner face of the boss, as clearly shown in Fig. 2. The boss 18 is 85 provided on its upper surface with another smaller boss 20.

The closure is preferably made of a good grade of rubber in a mold and is vulcanized to provide the desired elastic properties. In 100

the type of closure as shown in Figs. 1 to 7 inclusive the mold is of elliptical form to make the portion 16 of elliptical form as shown in Fig. 6, the major axis of the ellipse being at right angles to the boss 18. This elliptical closure is also provided with a molded narrow slot 21 approximately the length of the cavity 19 and extending from the top surface of said cavity through the boss 18 to a point slightly spaced from the top of the boss 20. The closure may be provided with a band 21' to assist the closing action.

To secure the closure upon the neck of the tube the annular portion 16 of the closure 15 is placed against the flange 13 of the neck 12 in a groove formed by the elements 13, 14, and 22. The end portion of the neck, which forms a peripheral wall as shown in Fig. 1 and indicated by 22, is then spun or otherwise turned over the annular portion 16 as indicated by 23 in Fig. 2 to hold the closure 15 securely in the neck 12.

When the elliptically formed closure member 15 is inserted in the cylindrical neck 12 the slot 21 is closed by the distortion from the elliptical shape to the cylindrical shape so that the walls of the slot are made to tightly engage each other.

After the closure 15 has been secured in place the tube 10 is filled with the desired ingredient which may be dental cream. The tube is then ready for the consumer. When one desires to use the contents of the tube it is necessary to merely cut off the boss 20 with a knife or any sharp instrument. When the boss 20 has been removed the slit 21 will be exposed and it is then only necessary to apply pressure to the tube 10 to force the contents out through the slit 21 which opens as shown in Fig. 7. After the pressure on the tube has been removed the elasticity of the closure forces the slit closed again as shown in Fig. 3.

In Figs. 8 and 9 I have shown a closure 25 having an annular basal portion 26 and a hemispherical end portion 27 having therebeneath a cylindrical cavity 28.

This closure is made in a circular mold and vulcanized but with no slot, and the outer periphery of the base 26 is of the same diameter as the inner face of the neck 12. After the closure 25 has been removed from the mold and cooled sufficiently the manufacturer cuts a slit 29 in the end 27 with a thin sharp instrument. The closure 25 is shown as secured in the neck of the tube in the same manner as the previously described closure 15. To prevent the accidental opening of the slit 29 and to prevent the entrance of air I cover the end portion 27 of the closure with wax, gelatine or other sealing compound, which forms a seal over the end portion 27 as indicated at 30 in Fig. 8.

In Figs. 10, 11, and 12 I show a closure similar to that shown in Fig. 8, but I show a dif-

ferent means of providing the closure with a valve port. In this form the valve opening is preferably made by the user by cutting a slit thereon although it will be understood that it may also be made by the manufacturer, in which case the end 27 would be covered with a sealing compound as previously described.

To make a valve opening 31 the tube 10 is placed under pressure, thus causing the contents of the tube 10 to stretch the end 27 as shown in Fig. 11. Tension may also be applied by stretching the closure. Then a sharp instrument such as a large needle 32 is forced through the end 27 to form a small hole communicating from the outer periphery of the same to the cavity 28. The pressure is then released and the instrument withdrawn and the contents of the tube may be withdrawn at will.

After the needle is withdrawn and the pressure on the closure is released, the end 27 of the closure resumes its normal position as shown in Fig. 10, and closes the small hole formed by the piercing instrument, thus preventing air from entering the tube and holding the contents of the tube.

In Figs. 13 and 14 I have shown a slightly modified form of closure retaining means and a modified form of closure. In this case the collapsible tube 35 is provided with a conical end portion 36 having a cylindrical neck 37 integral therewith. The neck 37 has a circular flange 39 formed integral therewith on its inner surface.

A closure such as used with this type of neck is indicated generally at 40 and comprises a conical basal portion 41 and a hemispherical end portion 42 having therebeneath a cylindrical cavity 43. Through the end portion 42 there is formed a valve slit 44. This closure is made elliptical and vulcanized with a slot 44 formed therein at the time of molding as previously described. To secure the closure 40 to the tube the base 41 of the closure is set on a circular flange 39 in the neck 37 and then the extreme end portion of the neck 37 is spun over the outer periphery of the base 41 as indicated at 45. The tube is then filled in the customary manner after which the end portion 42 is covered with a suitable seal which may be paraffin to form a seal 46 over the slit 44. In this manner the tube is delivered to the consumer.

In Figs. 15, 16 and 17 I have shown a further modification wherein the tube is provided with a neck 50 which is integral therewith. This neck is provided with a conical top portion 51 provided with an elongated opening 52. The closure is indicated generally at 53 and is similar to the closure 15 shown in Fig. 1. It comprises a body having an elliptical base 54 and an end portion 55. The end portion consists of a transversely extending boss 56 having on its upper surface another boss 57. The boss 56 is so arranged

as as to provide a transverse cavity 58. The closure has a slit 59 above this cavity. This form of closure is also preferably made in an elliptical mold and has the slot 59 formed at the time of molding.

5 This closure is inserted into the neck from the large end of the tube and the boss 56 fits snugly in the opening 52 of the top portion 51 of the neck. After the closure has been 10 placed in position a ring 60 of slightly larger diameter than the inner surface of the neck, is forced in the neck until it abuts the bottom of the base 54 of the closure and securely holds the same against the conical top portion 15 51 of the neck. If desired the ring 60 may be spot welded or otherwise held in place. The tube is then filled in the usual manner and is ready for the user.

As with the closure 15 previously mentioned it is necessary for the user to first expose the valve slit before the contents of the tube can be extruded therefrom. This is done by removing the boss 57 with some sharp instrument. The metal edges of the slot 52 20 exert a pressure against the outer surface of the boss 56 and tend to force the same inwardly and thus assist the closing action of the valve slit 59.

In Fig. 18 I show a modified form of the 30 closure 53. This modification consists merely of adding to the outer surface of the boss 56 adjacent the top thereof a flange or bead 61. When the closure is in place this bead is on the outside of the conical top portion 51 35 of the neck 50 and covers the edges of the slot 52. The bead 61 helps to prevent the dislocation of the closure and provides more material around the boss which assists in the closing of the valve. The bead is also ornamental and gives the end of the neck a more 40 finished appearance.

Although in the foregoing description I have referred to my invention as embodied in a collapsible tube, I wish it to be understood 45 that it may be used for other purposes if desired.

What I claim is:

1. A collapsible tube having a flexible body and a relatively stiff end, said end having a 50 cylindrical collar thereon, and a closure for said end, said closure having a normally elliptical base distorted to fit said collar.

2. In combination with a collapsible tube having a flexible body and a relatively stiff 55 end and having a cylindrical groove thereon, a closure cap having a normally elliptical base portion, said base portion fitting said groove.

3. In combination with a collapsible tube 60 having a flexible body and a relatively stiff end, and having a cylindrical groove thereon, and a rubber closure cap having a 65 normally elliptical base portion, said base portion fitting said groove and secured therein, said closure member having a dispensing

aperture therein, said aperture being normally closed by tension produced when the elliptical base is distorted to cylindrical shape.

4. A collapsible tube having a flexible body and a relatively stiff end, said end having a 70 cylindrical groove therein, and a closure comprising a flexible member having a base portion fitted in said groove, said closure being normally elliptical in shape and normally having a preformed slot therein, said slot extending along the minor axis of said ellipse, and a member integral with said closure for closing said slot.

5. The combination of a collapsible tube having a flexible body and a relatively stiff 75 end, said end having a cylindrical groove thereon, and a rubber closure cap having a normally elliptical base portion, said base portion fitting said groove, said closure member having a dispensing aperture therein, 80 the opposed walls of the closure defining said aperture being forced into direct engagement by tension produced when the elliptical base is distorted to cylindrical shape.

6. The combination of a collapsible tube 85 having a flexible body and a relatively stiff end, said end having a cylindrical collar thereon, a flange extending inwardly from said collar and having a second collar at its inner end spaced from said first collar and a 90 closure comprising a flexible member having a thickened basal portion, said basal portion being arranged between said collars and said outer collar being spun over onto the thickened basal portion, said closure being 95 normally elliptical in shape and having a preformed slot therein, said slot extending along the major axis of said ellipse, and a member integral with said closure for closing said slot.

7. A collapsible tube having a flexible body and a relatively stiff end, said end having a 100 groove therein, the wall of said groove being cylindrical and a resilient closure having a normally elliptical base fitting said groove, 105 said closure having a dispensing aperture.

In testimony whereof, I hereunto affix my signature.

ARTHUR E. SMITH.
